UNITED STATES PATENT OFFICE

FRED M. POORE, OF SEATTLE, WASHINGTON

BURNER

Application filed November 25, 1929, Serial No. 409,735. Renewed August 15, 1932.

The invention is an apparatus that may readily be installed in a fire box of a furnace, which will aid combustion, and spread the flames toward the side walls thereby increasing the efficiency of the fire, and which is particularly adaptable for burning oil or the like.

The object of the invention is to provide a device which will create a downward draft 10 into the center of the fire and spread the flame of a fire toward the side walls.

Another object of the invention is to provide a burner for oil or the like which is so arranged that the oil passing into the fire box will come into contact with air passing through the fire box and mix with the said preheated air before igniting.

Another object of the invention is to provide a conical baffle in combination with a vertically positioned burner tip to spread the burning gases from the tip.

A further object of the invention is to provide a suitable drip pan in combination with a burner which will collect escaping oil and shut off the feed when the escaping oil reaches a predetermined amount.

And a still further object of the invention is to provide a casing adaptable to surround a burner tip which will spread the gases both before and after burning.

With these ends in view the invention embodies, a vertical tubular chamber positioned in the center of a fire box with an enlarged section adjacent the lower end and a horizontal baffle forcing gases passing downward toward the outside of the said enlarged chamber, and a fuel entry pipe extending downward through the said vertical tubular chamber to a point adjacent the lower end of the said enlarged chamber. A drip pan with a conical member in the center may be used in combination with the said device and a connection may be made from the drip pan to an automatic shut-off valve located in the fuel supply pipe. A stack temperature control device may also be used to operate the shut-off valve.

Other features and advantages of the invention will appear from the following de-

scription taken in connection with the drawing, wherein:

Figure 1 is a vertical section through a furnace showing the device as it may be installed in a heating furnace.

Figure 2 is a sectional plan through the enlarged chamber of the vertical tubular chamber shown in Figures 1 and 3, looking downward, showing the horizontal baffle, the fuel supply pipe in the center with a pipe surrounding it, and the lower end of the vertical tubular chamber in dotted lines, and with the heater or furnace walls omitted.

Figure 3 is a view showing an alternate design.

In the drawing the device is shown as it would be made, wherein numeral 1 indicates the vertical tubular casing, numeral 2 the oil supply pipe, and numeral 3 the drip pan.

The vertical tubular casing 1 may be of any suitable shape or size and may be arranged in any suitable manner so that it will be adaptable to be installed in a furnace of any suitable type. In the design shown this member is positioned in the center of the fire box and extends through a chamber 4 in the front 5 of the fire box which is indicated by the numeral 6. The upper end is provided with a strap 7 to hold the device in place, however, it is understood that it may be held by any other suitable means. The lower part of the casing 1 is provided with an enlarged section 8 having a horizontal baffle 9 positioned in the central part thereof and held by legs 10 and it will be observed that below the section 8 is another section 11 which is comparatively of the same size as the upper part of the casing. It is understood that this casing and also the enlarged chamber 8 may be made of any suitable material and of any suitable thickness.

The oil entry or supply pipe 2 may also be of any suitable size and arranged in any suitable manner. In the design shown the pipe 2 is placed through a small pipe 12 and the pipe 12 is attached to the front of the casing and extends horizontally and then downward through the center of the casing 1 and through the baffle 9 to the point 13 in the lower part of the enlarged chamber 8. The pipe 2 also

extends continuously through the pipe 12 to the point 13. It will be observed that as oil or the like passes through this pipe it will form a jet in the lower section 11 and it will be atomized and mixed with the heated air passing downward through the chamber 1. It will be noted that with the chamber 1 positioned in this manner the air will be drawn into the fire through the center of the fire box so that it will be heated thereby providing pre-heated air which is mixed with the fuel to form the fire. The pipe 2 may be provided with a valve as indicated by the numeral 14 and may be connected to an automatic cut-off valve 15 and the valve 15 is connected by a pipe 16 to the drip pan 3 which is positioned in the lower part of the furnace so that any oil that is not burnt will pass to the cut-off valve and shut off the supply. A conical member 17 may be placed in the center of the drip pan 3 or may be positioned directly below the lower end of the chamber 1 to spread the gases in all directions as they are injected into the fire box. The burner may be provided with wires 18 and a coil 19 and the wires may be positioned so that they will extend into the fire box to the point 20 which is directly below the lower end of the member 12 so that a spark may be supplied either continuously or when desired to ignite the fuel. It is understood that this sparking means may be omitted if desired.

A stack temperature control device 21 may also be provided which is connected to the shut-off valve, through a connection 22, in such a manner that it will operate the valve when the stack temperature drops below a predetermined degree.

The cross section shown in Figure 2 is through the chamber 8 and shows the position of the baffle 9 and the small fuel supply tube 2 with the larger tube 12 surrounding it. The tube 12 protects the fuel from the extreme heat of the fire as the stack draft will draw air through this small tube and also through the casing 1 at a comparatively high velocity.

In the design shown in Figure 3 the burner is installed in a heater or stove 23, with the casing 1 extending directly out of the top of the stove so that the draft will be drawn directly downward as the fire burns, and the stack becomes heated. The device will operate similar to that shown in Figure 1.

It will be understood that other changes may be made in the construction without departing from the spirit of the invention, one of which changes may be in the design or shape of the section 8, another may be in the positioning of the upper or open end of the casing 1 at any other suitable point, another may be in the changing of the location of the oil entry pipe 2, and still another may be in the use of the device in a furnace of any other type.

The construction will be readily understood

from the foregoing description. In use the device may be provided and installed as shown with the oil supply pipe connected to any suitable means for supplying oil and by opening the valve 14 and igniting the fuel at the lower end of the section 11 of the chamber 1 the fire will be started and it will be observed that the fuel will be spread as it is ignited and the flames will pass upward against the inner surface of the outer wall of the firebox so that practically all of the heat will come into contact with the wall instead of passing upward through the center as is normally the case with practically any furnace. The outer surface of the walls of the section 8 also assist in deflecting the flames outward. It will be noted that the draft is drawn through the casing 1 and as soon as the stack becomes heated it will draw the air downward through this casing with considerable velocity and thereby through the center of the fire, so that its temperature will be raised to a high degree when it mixes with the oil, or other fuel. It will therefore be observed that the device will have the highest possible efficiency as the hot point normally existing in the center of the furnace is spread outward against the fire-box walls, and the air mixing with the fuel passes downward through the center of the firebox so that its temperature is raised to a very high degree before it mixes with the fuel at the point of combustion. This air may be controlled by a damper, as indicated by the numeral 24, at the outer end of the casing 1, as shown in Figure 3.

Having thus fully described the invention what I claim as new and desire to secure by Letters Patent, is:

1. In a device of the class described, a furnace, a vertical tubular member positioned in the center of the fire box of the furnace, an enlarged chamber in the said vertical member adjacent the lower end thereof, a fuel supply pipe extending downward through the vertical member and chamber to a point a short distance from the lower end, and a conical member with the vertex toward and in axial alignment with the said vertical chamber and spaced a short distance from the lower end thereof, the said tubular member with the supply pipe in the same relation thereto extending to the outer wall of the furnace.

2. In a device of the character described, a vertical tubular member, an enlarged chamber with outwardly and upwardly inclined sides in the said tubular member adjacent the lower end thereof, a fuel supply pipe extending downward in the said tubular member and terminating a short distance from the end thereof, and a conical member spaced a short distance from the end of the said tubular member and in axial alignment therewith, said device being adaptable to be posi-

tioned in the fire box of a furnace, the said tubular member with the supply pipe in the same relation thereto extending to the outer wall of the furnace.

- 5 3. In a device of the character described, a vertical tubular member, a furnace in which the said vertical tubular member is located, an enlarged chamber with outwardly and upwardly inclined sides in the said tubular member adjacent the lower end thereof, and a fuel supply pipe extending downward in the said tubular member and terminating a short distance from the end thereof, the said tubular member with the supply pipe in the
- 10 same relation thereto extending to the outer wall of the furnace.

4. In a device of the character described, a vertical tubular member, an enlarged chamber with outwardly and upwardly inclined sides in the said tubular member adjacent the lower end thereof, a fuel supply pipe extending downward in the said tubular member and terminating a short distance from the end thereof, and a horizontal baffle plate in the said enlarged chamber closing the center of the chamber and leaving a space around the outer edge.

5. In a burner of the class described, a furnace, a vertical tubular member positioned in the center of the fire box of the said furnace and terminating a comparatively short distance from the bottom of the said fire box, an enlarged chamber with outwardly and upwardly sloping sides formed in the said tubular member a short distance from the lower end thereof, a horizontal baffle plate in the said enlarged chamber, a fuel supply pipe extending downward through the tubular member and through the baffle and terminating at a point adjacent the lower end of the said enlarged chamber, a conical member positioned below and spaced from the lower end of the said tubular chamber, and a drip pan below the said tubular member.

45 6. In a device of the class described, a furnace, a vertical tubular chamber positioned in the center of the fire box of the furnace, a connection from the said vertical chamber to the exterior of the furnace, an enlarged chamber in the said vertical chamber adjacent the lower end, a fuel supply pipe extending through the vertical chamber to a point a short distance from the lower end, a similar tubular casing surrounding the said fuel supply pipe and positioned in the center of the said tubular chamber, and a conical member in axial alignment with the said vertical chamber and spaced a short distance from the lower end thereof, the said tubular member with the supply pipe in the same relation thereto extending to the outer wall of the furnace.

7. In a device of the class described, a furnace, a vertical tubular chamber positioned in the center of the fire-box of the furnace, a

connection from the said vertical chamber to the exterior of the furnace, an enlarged chamber in the said vertical chamber and adjacent the lower end, a fuel supply pipe extending through the vertical chamber to a point a short distance from the lower end, a similar tubular casing surrounding the said fuel supply pipe and positioned in the center of the said tubular chamber, and a horizontal baffle plate in the said enlarged chamber closing the center of the chamber and leaving a passage around the outer edge of said plate.

In testimony whereof I affix my signature.

FRED M. POORE.
